US00D663016S

(12) **United States Design Patent**
Figurski et al.

(10) **Patent No.:** **US D663,016 S**
(45) **Date of Patent:** **** Jul. 3, 2012**

(54) **LAVATORY SYSTEM WITH INTEGRATED
HAND DRYER**

(75) Inventors: **Mark A. Figurski**, Hartland, WI (US);
Jason M. Renner, Greenfield, WI (US);
John M. Loberger, Germantown, WI (US); **Kevin M. Kohlwew**, Port Washington, WI (US); **Cory R. Boudreau**, Madison, WI (US); **Scott I. Biba**, Highland, WI (US); **Nicholas S. Reback**, Madison, WI (US)

(73) Assignee: **Bradley Fixtures Corporation**,
Menomonee Falls, WI (US)

(**) Term: **14 Years**

(21) Appl. No.: **29/400,281**

(22) Filed: **Aug. 25, 2011**

(51) **LOC (9) Cl. 23-02**

(52) **U.S. Cl. D23/291; D23/271; D28/54.1**

(58) **Field of Classification Search D23/271, D23/284, 286, 308; 4/662, 619, 630, 638; D28/54.1; D24/185**

See application file for complete search history.

CLAIM

The ornamental design for a lavatory system with integrated hand dryer, substantially as shown and described.

DESCRIPTION

This application claims priority from U.S. patent application Ser. No. 13/088,793, filed on Apr. 18, 2011, the entirety of which is expressly incorporated by reference herein.

FIG. 1 is a raised perspective view of a first embodiment of a lavatory system;

FIG. 2 is a front perspective view of the lavatory system of FIG. 1;

FIG. 3 is a left-side elevation view of the lavatory of FIG. 1; FIG. 4 is right-side elevation view of the lavatory of FIG. 1; and,

FIG. 5 is a top plan view of the lavatory of FIG. 1.
